UNITED STATES PATENT OFFICE.

CHARLES J. PILLIOD, OF TOLEDO, OHIO, ASSIGNOR TO DANIEL SEARLES, TRUSTEE,
OF TOLEDO, OHIO.

VALVE GEAR.

Application filed February 10, 1921. Serial No. 443,741.

To all whom it may concern:

Be it known that I, CHARLES J. PILLIOD, a citizen of the United States, and a resident of Toledo, in the county of Lucas and 5 State of Ohio, have made an Invention Appertaining to Valve Gear; and I do hereby declare the following to be a full, clear, and exact description of the invention, such as will enable others skilled in the art to 10 which it appertains to make and use the same, reference being had to the accompanying drawings, and to the characters of reference marked thereon, which form a part of this specification.

15 This invention relates to reverse gears, and particularly to those of the radial type for use in connection with the engine valves of locomotives.

20 The object of the invention is to simplify gears of the type described heretofore used and also to adapt them for operation entirely from the cross-heads instead of the drive wheel cranks of locomotives, thereby producing a radial type valve gear that is 25 not subjected to distortion by the rise and fall of the engine, as is the case with gears receiving their accelerated travel from the drive wheel cranks.

30 The invention is fully described in the following specification, and while, in its broader aspect, it is capable of embodiment in numerous forms, two embodiments only thereof are illustrated in the accompanying drawings, in which,—

35 Figure 1 is a fragmentary side elevation of a locomotive equipped with my improved valve gear. Fig. 2 is a rear elevation of the reverse mechanism of the gear, with parts in section and parts removed. Fig. 3 is a side 40 elevation thereof in forward motion position. Fig. 4 is a fragmentary plan view of the gear arrangement at both sides of the locomotive and the connection therebetween. Fig. 5 is a fragmentary side elevation of a 45 locomotive with a different form of radial type valve gear direct connected to a cross-head, and Figs. 6, 7 and 8 are different details thereof.

50 Referring to the drawings, 1 designates a locomotive frame, 2 the drive wheels thereof, 3 an engine cylinder, 4 the cross-head, the rod 5 from which projects into the cyl-

inder and connects with the piston, and 6 the valve stem guide.

The reverse mechanism for the valve gear, 55 one of which is located at each side of the locomotive, is mounted in a bracket or frame part 7 carried on the cross-head guide yoke 8 and comprises a reverse-yoke 9 journaled at the ends of its arms in the bracket 60 7 at 10, a radius-yoke 11 pivotally suspended from the upper end portion of the yoke 9, a radius-lever 12 fulcrumed in the lower end portion of the radius-yoke 11, and the bell-crank-lever 13 fulcrumed in the bracket 65 7 and connected at one end to the upper end of the radius-lever 12. The radius-lever 12 is connected at its lower end to the cross-head 4 by a union-rod 14, instead of being connected to the drive wheel crank, as has 70 heretofore been the custom. The upper end of the reverse-yoke 9 is connected by a rod 15 to any suitable control means, as is well understood in the art, whereby the reverse-yoke may be shifted forward or backward 75 at the will of the operator. The downwardly extending arm of the bell-crank-lever 13 is connected by a radius-bar 16 to a rocker-arm 17 fixed to and projecting downward from a shaft 18 which extends entirely 80 across the locomotive and is journaled in suitable brackets 19. The shaft 18 at the opposite side of the locomotive has an upwardly projecting rocker arm 20, which is connected by a radius-rod 21 to the upper 85 end of the combination-lever 22, which is carried by the valve stem cross-head 23 mounted in the guide 6 of the associated engine.

The reverse mechanism at the opposite 90 side of the locomotive to that above described has its radius-bar 16 connected to a rocker-arm 24 projecting downward from the adjacent end of a hollow shaft 25, which is sleeved on the shaft 18 and extends to the 95 opposite side of the locomotive, having at such side a downwardly extending rocker arm 26, which is connected by a radius-rod 27 with the upper end of the combination-lever 28 carried by the valve-stem cross-head 23 of the associated engine. Each 100 combination-lever 22, 28 has its lower end connected to the associated cross-head 4 by a union link 29.

The operation of my improved valve gear is as follows: Upon a running of the locomotive the cross-head 4 of each engine communicates a rocking movement to the connected radius-lever 12 around both its bearing in the radius-yoke 11 and the bearing of the radius-yoke in the reverse yoke 9, and this motion in turn rocks the bell-crank-levers 13. The lever 13 at the right side of the locomotive, in the present instance, imparts a rocking movement to the cross shaft 18, which is connected at the opposite side of the locomotive through the arm 20 and radius-rod 21 with the combination-lever 22 of the engine at that side, while the movement of the other bell-crank-lever 13 effects a rocking of the hollow shaft 25, which in turn communicates a rocking movement to the combination-lever 28 at the right side of the locomotive through the rocker-arm 26 and radius rod 27. It is well understood in the art that the combination-lever for each engine receives its lap and lead movement from the cross-head of the associated engine and it receives its accelerated valve movement from the reversing mechanism at the opposite side of the locomotive.

One of the novel features of my gear consists in connecting the radius lever 9 of a reversing mechanism direct through links 12 and 14 to the cross-head instead of to the drive wheel crank at such side of the locomotive for imparting the accelerated motion to the valve of the engine at the opposite side of the locomotive, whereby the rise and fall of the locomotive on its springs has no distorting effect on the accelerated movement produced by the valve gear. In practice this is a very important feature, it being found that losses due to distorted valve gears lower the efficiency of a locomotive at times as much as 30 per cent.

Another novel feature of the invention resides in connecting a reversing mechanism at one side of the locomotive to a combination lever, at the other side of the locomotive through respective shafts each having a pair of rocker arms with one connected to the operating reversing mechanism and the other to the upper end of the associated combination lever. This arrangement very materially simplifies the valve gear construction, reduces the number of parts, and permits easier application to old designs of engines.

A slightly different form of radial type of valve gear from that above described and which is directly connected to and operated by the cross-head is illustrated in Figs. 5 to 8. In this form of gear 30 designates the reverse-yoke, 31 the radius yoke and 32 the radius-lever all mounted and connected, as described in connection with the first form, and the radius-lever being con-

nected to the cross-head 33 by a union-link 34, whereby the reverse mechanism is operated from the cross-head. The upper end of the radius-lever is connected to a rocker-arm 35 projecting from a cross-shaft 36, the opposite end of which is provided with a downwardly extending rocker arm that is connected by a link to the combination-lever at that side of the locomotive. The valve gear at the opposite side of the locomotive has its radius-lever connected by a rocker-arm to a cross-shaft 37, the near end of which carries a downwardly extending rocker arm 38 that is connected by a radius-rod 39 to the associated combination lever 40, the mounting and operation of which lever is the same as described in the other form of the invention. The specific form of this valve gear is claimed in a copending application No. 443,742.

The term "radial type" gear as used herein is commonly understood in locomotive practice as referring to valve gears in which the reversing means comprises a plurality of parts each mounted for rocking movements and having true pivotal, as distinguished from sliding, connection with each other.

I wish it understood that my invention is not limited to any specific construction, arrangement or form of the parts, as it is capable of numerous modifications and changes without departing from the spirit of the claims.

Having thus described my invention, what I claim as new, and desire to secure by Letters Patent, is,—

1. In a locomotive, the combination with an engine operated cross-head at each side and an engine valve at one side, of a lap and lead mechanism connected to the valve and to one cross-head, and a reversing mechanism of the radial type connected to the lap and lead mechanism and having its radius lever directly connected to and operated by the other cross-head.

2. In a locomotive, the combination with an engine operated cross-head at each side and an engine valve at one side, of a valve gear mechanism having a lap and lead means including a floating combination lever connected to one cross-head and to the valve and having a reversing means of the radial type connected to the lap and lead means and including a radius lever directly connected to and operated by the other cross-head.

3. In a locomotive, the combination with an engine operated cross-head at each side and an engine valve at one side, of a valve gear mechanism of the radial type connecting a cross-head and valve at opposite sides of the locomotive and operated by the former, said mechanism comprising a reversing mechanism, a cross-shaft, a float-

ing combination lever connected to the valve, a rocker arm on the shaft connected to and operated by the reverse mechanism, and a second rocker arm on the shaft connected 5 to the upper end of the combination lever and imparting accelerated motion thereto, the other end of the combination lever be-

ing connected to and having lap and lead movement imparted thereto from the other cross-head.

In testimony whereof I have hereunto signed my name to this specification. 10

CHARLES J. PILLIOD.
